 graphie m. b. H., Berlin, Germany, a corpora-
 tion of Germany

Application March 12, 1938, Serial No. 195,481
 In Germany March 8, 1937

6 Claims. (Cl. 250—33)

This invention relates to an arrangement for matching a short-wave antenna whose length can be adjusted with an energy line.

The invention relates to an improvement in the matching arrangement described in my co-pending application No. 168,120, filed October 9, 1937. The subject matter of the co-pending application is a line section inserted between the energy line and an antenna whose length is so varied that it is always equal to a quarter wave and the said length of the line section is likewise varied with the antenna length to always equal a quarter wave, while its wave resistance is equal to the geometrical mean value between the wave resistance of the energy line and that of the bottom point of the antenna. The accompanying figure shows a practical embodiment of the present invention. As shown in the figure, the tubular antenna 1 is to be mechanically supported against the outer conductor 3 by an insulator 7 at the lower end of which the antenna is pulled over the inner conductor 5 of the energy line. This insulator is fixedly secured to the lower end of the antenna, so that when the length of the antenna changes, the insulator moves in the outer tube 3. The insulator must be dimensioned with respect to mechanical considerations and must be very strong. This entails a considerable increase in the capacity at the place at which the antenna conductor of the energy line joins the inner conductor of the energy line.

In accordance with the invention, the effect of this capacitive increase will be compensated in that at the place at which the transformation piece joins the actual lead-in cable, there is again provided an insulator 8 of a size corresponding to insulator 7. The invention is based upon the known fact that a wattless resistance placed at a line appears at a distance equal to a quarter wave with its reciprocal value. Since the transformer section has a length always equal to a quarter wave, this fact can, in accordance with the invention, be utilized successfully at any desired tuning of the antenna for compensating the disturbing insulator capacity. As viewed from the cable the effects of the insulators 7 and 8 eliminate each other at the input of the transformation piece, so that the entire arrangement operates as if no insulators were present. The insulator 8 remains fixed at the same place while the insulator 7 moves with the antenna conductor 1 such that the distance between the insulators is equal to a quarter wavelength.

I claim:

1. A short wave antenna system comprising a

variable length vertical aerial conducting tube adjustable to have an effective free length equal to an odd multiple including unity of one-quarter of the length of the operating wave, a vertical concentric line section having an outer conductor 5 and inner conductor, said aerial tube being arranged to slide over and contact the inner conductor of said line, an energy feeder also in the form of a concentric line coupled to the bottom of said vertical concentric line section the length 10 of said inner conductor of said line section as measured from said feeder to the nearest point of contact with said aerial tube being substantially equal to the effective free length of said aerial, an insulator attached to said aerial tube 15 and movable therewith spacing said tube from said outer conductor, and a second insulator between said inner conductor and said outer conductor arranged at a distance equal to a quarter of the length of the operating wave from said 20 first insulator and so dimensioned that the capacity effect of said first insulator is compensated thereby.

2. A short wave antenna system comprising a vertical aerial conducting tube adjustable to an odd multiple including unity of a quarter wave length, a concentric line transformer section having an outer conductor and an inner conductor, said aerial tube being arranged to slide over and contact the inner conductor of said section, a 30 first insulator attached to the lower end of said aerial tube and movable therewith to space said tube from said outer conductor the length of said inner conductor between the end of said aerial tube and the bottom of the transformer section 35 being constantly equal to the effective free length of the aerial tube, and a second insulator at the bottom of said transformer section so dimensioned that the capacity effects of said first insulator are compensated thereby.

3. A short wave antenna system comprising a variable length aerial conductor adjustable to have an effective free length equal to an odd multiple including unity of one-quarter of the length of the operating wave, a feeder and a line 45 having a length equal to the effective free length of said aerial conductor connecting said feeder to said aerial conductor, said conductor being slidable over said line whereby a change of length of said aerial conductor simultaneously changes 50 the length of said line in equal amount, an insulator surrounding the end of said aerial conductor surrounding said line, a second similar insulator at the end of said line remote from said aerial conductor whereby the capacity effect of 55

said first insulator is compensated for by said second insulator.

4. A short wave antenna system comprising a variable length aerial conductor adjustable to have an effective free length equal to an odd multiple including unity of one-quarter of the length of the operating wave, a concentric line feeder and a concentric line matching section having a length equal to the effective free length 5 of said aerial conductor connecting said feeder to said aerial conductor, said section having an outer sheath and an inner conductor, said aerial conductor being slideable over said inner conductor whereby a change of length of said aerial 10 conductor simultaneously changes the effective length of said matching section in equal amount, an insulator surrounding the end of said aerial conductor surrounding said central conductor, a second similar insulator at the end of said matching 15 section remote from said aerial conductor, said second insulator being so dimensioned that the capacity effect of said first insulator is compensated thereby.
5. A short wave antenna system comprising a variable length vertical aerial conductor tube adjustable to have an effective free length equal to an odd multiple including unity of one-quarter of the length of the operating wave, a vertical concentric line section having an outer conductor 20 and inner conductor, said aerial tube being arranged to slide over and contact the inner conductor of said line, an energy feeder also in the 25
- 30

form of a concentric line coupled to the bottom of said vertical concentric line section the length of said inner conductor of said line section as measured from said feeder to the nearest point of contact with said aerial tube being substantially equal to the effective free length of said aerial, an insulator attached to said aerial tube and movable therewith spacing said tube from said outer conductor, and a second insulator similar to said first insulator between said inner conductor and said outer conductor arranged at a distance equal to the effective free length of said aerial whereby the capacity effect of said first insulator is compensated thereby. 5

6. A short wave antenna system comprising a vertical aerial conductor tube adjustable to an odd multiple including unity of a quarter wave length, a concentric line transformer section having an outer conductor and an inner conductor, said aerial tube being arranged to slide over and contact the inner conductor of said section, a first insulator attached to the lower end of said aerial tube and movable therewith to space said tube from said outer conductor the length of said inner conductor between the end of said aerial tube and the bottom of the transformer section being constantly equal to the effective free length of the aerial tube, and a second similar insulator at the bottom of said transformer section whereby the capacity effects of said first insulator are compensated thereby. 10 15 20 25 30
